BARREL MOUNTING

Samuel G. Green, Gray, Ga.

Application July 8, 1940, Serial No. 344,369

4 Claims. (Cl. 89—14)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to means for mounting the muzzle end portion of an air cooled gun barrel, and is particularly adapted for use in fixed aircraft and similar fixed vehicular mounts where a blast tube is used to conduct the gases of explosion arising from firing through the cowling of the aircraft or other vehicle.

It is an object of the invention to so mount the muzzle end portion of the barrel of an automatic fixed gun in a blast tube that frequent dismounting for cleaning will be obviated.

It is a further object of the invention to mount the muzzle end portion of the barrel of an automatic fixed gun in a blast tube in a manner to positively preclude travel of gases between the barrel and blast tube rearwardly from the muzzle of the latter.

A still further object of the invention is to so mount the muzzle portion of the barrel of an automatic gun in a blast tube as to utilize the flow of gases under high velocity from the muzzle of the barrel to withdraw gases accumulating rearwardly of the muzzle between the barrel and blast tube, in a manner similar to the manner in which an injector functions.

In view of the relative high speeds at which present day aircraft travel; the long leads of the blast tubes necessary in the fixed installation of automatic guns on such craft; the intricacies of the fixed type of installation on such aircraft, which renders accessibility difficulty with frequent dismounting of the gun consequently rendered impractical; and the present increased gun firing rates, it has become imperative that the muzzle end bearing of the gun barrel be substantially self cleaning and lubricating, to obviate the necessity of frequent dismounting of the gun for cleaning; and that flow of gases rearwardly between the barrel and blast tube to the gunner's cockpit or similar station be prevented to eliminate placing the gunner under this handicap. Therefore, with these factors in mind it is a still further object of the invention to provide a barrel mounting for the muzzle end portion of the barrel of an automatic fixed mount gun that will in practice overcome the difficulties introduced by these factors.

The specific nature of the invention as well as other objects and advantages thereof will clearly appear from a description of a preferred embodiment

as shown in the accompanying drawings in which:

Fig. 1 is a longitudinal sectional view through the muzzle end portion of the barrel of an automatic gun of the type wherein the barrel has limited recoil and counterrecoil movement mounted in a blast tube also shown in fragmentary longitudinal section.

Fig. 2 is a view similar to Fig. 1 showing a slight modification.

Fig. 3 is sectional view showing a modification;

Fig. 4 is a sectional view showing a modified barrel wherein the use of a separate bearing and guide sleeve is eliminated.

Referring now to the drawing there is shown a barrel 10 suitably mounted for limited recoil and counter-recoil movement as is well known in the art. The barrel 10 is mounted within a stationary barrel jacket 11 and is guided in recoil

and counterrecoil movements adjacent its muzzle end by a cylindrical guide sleeve 12 suitably secured to the barrel in fluid sealed relation adjacent its forward end in such manner as to increase the effective cross sectional area of the forward end of the barrel. From its zone of attachment to the barrel the sleeve 12 extends rearwardly in circumferentially spaced relation to the barrel a suitable distance where it is terminated in an inwardly directed flange 13 which engages the barrel 10.

A cylindrical acceleration chamber forming member 14 is secured to the forward end of the barrel jacket 11 in axial prolongation thereof in any convenient manner and has its rear portion protruding within the muzzle end portion of the barrel jacket 11. The forward end portion of the sleeve 12 is externally reduced to form a seat for a bearing broaching ring 15 which may be preformed to fit the seat in the sleeve

12 or cast or deposited thereon as found most expedient and a cooperating bearing broaching ring 16 is provided within the member 14 adapted by its configuration to cooperate with the bearing broaching ring 15 in clearing the bearing surfaces between these two rings of deposits tending to collect thereon. Forwardly of the bearing broaching ring 16 a plug 17 having an axial projectile passage 18 is inserted within the member 14 and is designed to so constrict the forward end of the member 14 as to form a barrel accelerator or booster chamber 19.

Gases passing from the chamber 19 rearwardly past the rings 15—16 are emitted from within the member 14 by way of ports 20. The struc-

ture thus far described is similar to the corresponding structure in my copending applications Nos. 302,553 and 344,368, filed November 2, 1939, and July 8, 1940, respectively.

Rearwardly of the ports 20 the cylindrical member 14 is suitably formed to receive or provide a bearing 21 which receives the sleeve 12 in very accurately fitted bearing relation. The bearing ring 21 is interiorly grooved annularly to provide a plurality of longitudinally spaced grooves 22 which act in combination with the bearing surface on sleeve 12 to form a tortuous passage from one side of the bearing ring 21 to the other and thereby effectively prevent the flow of gases through the bearing between the sleeve 12 and member 14.

The blast tube 23 is of substantially the same inside diameter as the outside diameter of the barrel jacket 11 so as to snugly receive the latter and to further perfect the seal between the blast tube and barrel jacket a gasket G of any desirable material such as asbestos, is inserted between the blast tube and barrel jacket.

The sleeve 12, bearing broaching rings 15, 16, member 14 and bearing ring 21 may all be made of the same materials as suggested for the comparable parts in my copending applications above referred to.

In order to prevent injury to the bearing ring 21 by the relative hard broaching ring 15 when the barrel 10 is withdrawn from or inserted within the barrel jacket 11 and member 14 the sleeve 12 is formed to provide an annular ramp surface 24 which is so proportioned as to coact with a ramp surface 25 on member 14 in such manner as to ensure that the bearing broaching ring 15 will be substantially centered with respect to the member 14 and bearing ring 21 as the barrel muzzle portion is inserted within the member 14. It will of course be understood that the ramp surfaces 24 and 25 are so related as to prevent the barrel from becoming eccentric to such an extent with respect to the bearing 21 and member 14 that the broaching ring 15 can contact bearing 21 before the broaching ring 15 clears the bearing ring 21 upon withdrawal of the barrel from member 14.

In operation the accelerator chamber 19 will cause the gases of explosion to accelerate recoil of the barrel and a portion of the gases will escape past the bearing broaching rings 15, 16 which have a working clearance of one to four times as great as the working clearance between the bearing ring 21 and sleeve 12. Gases escaping past the rings 15 and 16 will be emitted from member 14 through the ports 20 located intermediate the rings 15, 16 and ring 21 into the annular space between the exterior of member 14 and interior of the blast tube 23. Because of the very accurate fit of bearing ring 21 with sleeve 12 and the construction of the ring the escape of gases past the ring 21 between its bearing with sleeve 12 is practically precluded. Likewise escape of gases rearwardly between the barrel jacket 11 and blast tube 23 is precluded by the accurately interfitted relation of these members and the interposition of the gasket G therebetween. Emission of gases at a high velocity from the projectile passage 18 in plug 17 creates a region of lower pressure axially of the blast tube and consequently gases under reduced velocity head and accompanying increased pressure head, such as the gases emitted from ports 20, are forced to travel to the axial region of lower pressure 75

where they escape from the blast tube. This application of the injector principle is advantageously employed in the instant case as it provides a path of ready escape for the gases which escape rearwardly past the rings 15 and 16 forwardly within the blast tube thereby greatly increasing the effectiveness of the seals provided by the bearing ring 21 and gasket G. This advantage is of course greatly accentuated where as in certain aircraft installations the blast tube has a lead of several feet forwardly of the muzzle of the gun and is mounted in a high speed plane.

In the modification shown in Fig. 2 the sleeve 12' is secured to the barrel adjacent its forward end portion in the same manner as in Fig. 1, however, in this form of the invention the bearing element 15' is conveniently made integral with the sleeve 12' and formed with a cylindrical plane bearing surface 15''. Also the flange 13' of the sleeve is outwardly directed instead of being inwardly directed as in Fig. 1 and terminates in an annular bearing surface 13'' which engages the cylindrical member 14 in bearing relation. If desired circumferentially spaced bearing elements 26 may be formed on the sleeve to engage the barrel to provide a firm support for the sleeve on the barrel. In this manner increased bearing support for the muzzle of the barrel is obtained and circulation of air or other fluid between the sleeve 12 and barrel 10 afforded. Ports 27 may be formed between the flange 13' and bearing 21 to facilitate circulation of air to the bearing surfaces thereon and assist in preventing escape of gases rearwardly past the bearing 21.

To further increase the efficiency of the device a suitable gasket may be interposed between the sleeve 12' and member 14 intermediate the flange 13' and bearing 21, or within an annular groove in bearing surface 13'', however, in view of the bearing arrangement of this invention such practice will not be essential in the ordinary mount.

Furthermore the interior of the barrel jacket 11 may be so treated as to serve as a bearing for flange 13' of sleeve 12' directly, thereby eliminating that portion of member 14 extending rearwardly of bearing 21 as clearly shown in Fig. 3, however, the form shown in Fig. 2 is preferred.

In the presently preferred form of the invention a separate bearing and guide sleeve 12 or 12' is utilized as shown in Figs. 1, 2 and 3, however, if desired the separate sleeve may be eliminated and the muzzle portion of the barrel formed as shown in Fig. 4 so as to be directly received by the bearing ring 21, which in effect makes the barrel and sleeve integral functionally.

Having now described what is at present considered the preferred embodiment of the invention I claim:

1. In a barrel mounting adapted for use in mounting the muzzle end portion of a gun within a blast tube in combination, a barrel jacket, a cylindrical member mounted on the jacket in axial prolongation thereof with its rear portion terminating within the jacket, a bearing ring provided with interior annular grooves mounted within the rear portion of the member, a bearing broaching ring mounted within the member forwardly of said bearing ring in spaced relation, a barrel mounted within the barrel jacket, a sleeve secured to the barrel in fluid sealed relation adjacent its forward end, said sleeve being disposed within said bearing ring in accurately fitted bearing relation and being provided with a bearing broaching ring disposed in bearing relation with

said first recited bearing broaching ring, and said member being formed with ports intermediate said bearing and bearing broaching rings.

2. In a barrel mounting adapted for use in mounting the muzzle end portion of a gun within a blast tube in combination, a barrel jacket, a cylindrical member mounted on the jacket in axial prolongation thereof with its rear portion terminating within the jacket in an annular ramp surface, a bearing ring provided with interior annular grooves mounted within the rear portion of the member, a bearing broaching ring mounted within the member in forwardly spaced relation to said bearing ring, a removably mounted barrel mounted within the jacket, a sleeve secured to the barrel in fluid sealed relation adjacent its forward end and having a bearing portion extending rearwardly of the barrel in circumferentially spaced relation thereto, said sleeve being formed with a ramp surface intermediate its bearing portion and forward end portion adapted to cooperate with said first named ramp surface in centering the barrel relative to said member when interengaged, said barrel being mounted with the bearing portion of its sleeve disposed in

25 accurately fitted bearing relation within said bearing ring, a cooperating bearing broaching ring provided on the forward end portion of said sleeve disposed within said first recited bearing broaching ring and having a working clearance of one to four times the clearance of the sleeve and bearing ring, and gas emission ports provided in said member intermediate the bearing and bearing broaching rings.

10 3. The structure of claim 2 in combination with a blast tube fitted in close engagement around said barrel jacket and projecting forwardly of the cylindrical member, and wherein said cylindrical member is of smaller diameter externally than the internal diameter of the blast tube.

15 4. The structure of claim 2 in combination with a blast tube fitted in close engagement around said barrel jacket and projecting forwardly of the cylindrical member, gasket means interposed between said barrel jacket and blast tube and wherein said cylindrical member is of smaller diameter externally than the internal diameter of the blast tube.
